UNITED STATES PATENT OFFICE.

OLIVER R. BOYNTON, OF KANSAS CITY, MISSOURI.

BEATER OR MIXER.

Application filed October 5, 1925. Serial No. 60,491.

My invention relates to improvements in beaters or mixers adapted for beating eggs or mixing different materials.

One of the objects of my invention is to provide a beater or mixer of the kind described, which is simple, cheap, durable, not liable to get out of order, which is strong and easily retained in operative position, and which is easily operated and is efficient in operation.

My invention provides further a beater or mixer having novel and efficient beating or mixing means.

The novel features of my invention are hereinafter fully described and claimed.

In the accompanying drawing, which illustrates the preferred embodiment of my invention,

Fig. 1 is an elevation of my improved beater or mixer.

Fig. 2 is a vertical section on the line 2—2 of Fig. 1.

Fig. 3 is a cross section on the line 3—3 of Fig. 1.

Similar reference characters designate similar parts in the different views.

1 designates a bearing means comprising preferably a casting having at its upper end a handhold 2, and having below the handhold a lateral recess 3 in which is revolubly mounted a pinion 4 which is rigidly secured to and rotatable with a longitudinal supporting member comprising a rod 5 which is rotatably mounted in the bearing member 1 and which extends across the recess 3.

6 designates a supporting member comprising preferably a tube rotatably mounted in the bearing member 1 and having the same axis as the rod 5, the latter being extended through the tube 6 and being rotatably mounted on and attached to a supporting button 7, which is adapted to rest on the bottom of a container, not shown, which contains the material to be beaten or mixed.

45 Rotatably mounted on the bearing member 1 is a driving gear wheel 8 having an operating crank 9 and meshing with the pinion 4.

A pinion 10 is secured on and rotatable with the tube 6 and meshes with the teeth of the gear wheel 8 at a point diametrically opposite to the pinion 4, whereby, when the gear wheel 8 is rotated by means of the crank 9, the rod 5 and tube 6 will be simultaneously revolved on the same axis in opposite directions.

The bearing member 1 is disposed intermediate of the pinion 10 and a collar 11 which is secured on the upper end of the tube 6, whereby the latter is held from vertical movement in the member 1.

The beater or mixer is provided with two mixing devices, each comprising a wire helix in the form of an annulus. Secured to one helix 12 are upwardly extending supporting arms 13 which are fastened to the rod 5 below the tube 6.

The other helix 14 is outside of and concentric with the helix 12 and is, preferably, disposed adjacent to and in the same plane as the helix 12, and has fastened to it and revoluble with it upwardly extending supporting arms 15 which are fastened to and revolve with the tube 6.

In the operation of the beater or mixer, the button 7 is mounted in the container 75 which holds the materials to be beaten or mixed, and the driving gear is rotated by means of its crank 9, thereby revolving the helices 12 and 14 simultaneously in opposite directions by means of the pinions 4 and 10, 80 and rod 5 and tube 6.

By having the arms 13 and 15 fastened to the upper sides of the helices 12 and 14, and extending therefrom obliquely upwardly to and respectively fastened to the rod 5 and tube 6, clear spaces are afforded in the smaller helix and between the helices for the passage therethrough of the material which is being beaten, thereby assisting in the circulation and quick mixing thereof.

I do not limit my invention to the structure shown and described, as many modifications, within the scope of the appended claim, may be made without departing from the spirit of my invention.

What I claim is:—

In a beater or mixer of the kind described, two rotary members one revoluble around the other, means for simultaneously rotating said members in opposite directions, two concentric annular wire helices adjacent to each other, and arms respectively attached to said helices and extending obliquely upwardly from the tops of to and respectively fastened to said rotary members.

In testimony whereof I have signed my name to this specification.

OLIVER R. BOYNTON.
